UNITED STATES PATENT OFFICE.

JOHN W. ESHLEMAN, OF MOUNT JOY, PENNSYLVANIA.

DESIGN FOR A TOY BANK.

SPECIFICATION forming part of Design No. 35,864, dated April 15, 1902.

Application filed March 24, 1902. Serial No. 99,816. Term of patent 7 years.

To all whom it may concern:

Be it known that I, JOHN W. ESHLEMAN, a citizen of the United States, residing at Mount Joy, in the county of Lancaster and State of Pennsylvania, have invented and produced a new and original Design for Toy Banks, of which the following is a specification, reference being had to the accompanying drawings, forming a part hereof.

- 5 Figure 1 is a front elevation of a toy bank, showing my new design. Fig. 2 is a side view. As shown in the drawings, the leading or material feature of my design consists in the particular ornamentation of the front and sides of the bank, the front having a surrounding border a , the inner edges of the top and sides of which are scalloped, as at a' , while the lower edge of the bottom of said border, forming the lower edge of the bank, 10 is provided with a scallop a^2 . The door of the bank is also formed with a border a^3 , the inner edge of which is provided with a scallop a^4 . The sides, as indicated in Fig. 2, are each provided with a plain border b , inclosing fo-

15 liated ornamentations, and at one side of said border is a scalloped edge c .

The foliated ornamentation on the sides of the bank consists of two branches of grape-vine $b' b'$, extending from scrolls b^2 , each branch having a bunch of the fruit and leaflets. Beneath the said branches are leaf-scrolls $d d$, which in conjunction are formed 20 in the shape of a lyre. Inclosed within the leaf-scrolls $d d$ are the ornaments $e e$.

Both sides and the back of the bank are of 25 the ornamental design shown in Fig. 2.

Having described my invention, what I claim as new, and desire to secure by Letters Patent, is—

30 The design for a toy bank, as herein shown 40 and described.

In testimony whereof I have signed my name to this specification in the presence of two subscribing witnesses.

JOHN W. ESHLEMAN.
